Primary Examiner — Susan Moon Lee*(74) Attorney, Agent, or Firm* — Duane Morris LLP**(57) CLAIM**

We claim the ornamental design for a cradle for mobile terminal, as shown and described.

DESCRIPTION

FIG. 1 is a perspective rear view of a cradle for mobile terminal according to the present invention.

FIG. 2 is a perspective front view of the cradle for mobile terminal of FIG. 1.

FIG. 3 is a rear view of the cradle for mobile terminal of FIG. 1.

FIG. 4 is a front view of the cradle for mobile terminal of FIG. 1.

FIG. 5 is a right side view of the cradle for mobile terminal of FIG. 1.

FIG. 6 is a left side view of the cradle for mobile terminal of FIG. 1.

FIG. 7 is a top view of the cradle for mobile terminal of FIG. 1.

FIG. 8 is a bottom view of the cradle for mobile terminal of FIG. 1.

FIG. 9 is a perspective rear view of another embodiment of a cradle for mobile terminal according to the present invention.

FIG. 10 is a perspective front view of the cradle for mobile terminal of FIG. 9.

FIG. 11 is a rear view of the cradle for mobile terminal of FIG. 9.

FIG. 12 is a front view of the cradle for mobile terminal of FIG. 9.

FIG. 13 is a right side view of the cradle for mobile terminal of FIG. 9.

FIG. 14 is a left side view of the cradle for mobile terminal of FIG. 9.

FIG. 15 is a top view of the cradle for mobile terminal of FIG. 9; and,

FIG. 16 is a bottom view of the cradle for mobile terminal of FIG. 9.

Broken lines and unshaded portions contained within broken lines are not claimed.
